(57) **CLAIM**

The ornamental design for a flosser with a floss pick as shown and described.

DESCRIPTION

FIG. 1 is a front perspective view of a flosser with a floss pick showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top view of FIG. 1; and,

FIG. 7 is a bottom view of FIG. 1.

The broken lines on the floss pick handle form no part of the claimed design.
